United States Patent Office

Des. 196,444
Patented Oct. 1, 1963

196,444

SLED

Frank Ciborowski, 21 Lafayette St., Worcester, Mass.

Filed Apr. 22, 1963, Ser. No. 74,542

Term of patent 14 years

(Cl. D34—15)

FIG. 1 is a top plan view of a sled showing my new design;

FIG. 2 is a side elevational view thereof, looking in the direction of arrow 2 in FIG. 1, and

FIG. 3 is a rear elevational view, looking in the direction of arrow 3 in FIG. 2.

I claim:

The ornamental design for a sled, as shown.
